UNITED STATES PATENT OFFICE.

WILLIAM A. SCHRAUBSTADTER, OF ST. LOUIS, MISSOURI.

DESIGN FOR A FONT OF TYPE.

No. 39,411.

Specification for Design.

Patented July 7, 1908.

Application filed June 6, 1907. Serial No. 377,665. Term of patent 7 years.

To all whom it may concern:

Be it known that I, WILLIAM A. SCHRAUBSTADTER, a citizen of the United States, and a resident of the city of St. Louis and State of Missouri, have invented a new, original, and ornamental Design for a Font of Type, of which the following is a specification.

My design consists in the features shown in the accompanying drawing which forms part of this specification.

I claim:
The ornamental design for a font of type shown.

WM. A. SCHRAUBSTADTER.

In the presence of—
G. A. PENNINGTON,
JULIA B. MEGOWN.
